Primary Examiner — Kevin Rudzinski*Assistant Examiner* — Sean D Lough(74) *Attorney, Agent, or Firm* — Ichthus International Law, PLLC(57) **CLAIM**

The ornamental design for the ceiling light fixture, as shown and described.

DESCRIPTION

FIG. 1 is a perspective view of a ceiling light fixture in accordance with the present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines (where present) in all FIGS. 1-7 illustrate portions of the ceiling light fixture that form no part of the claimed design. Further, the broken line immediately adjacent to claimed surface(s) is a boundary of the claimed design.

1 Claim, 7 Drawing Sheets(56)
